EDWIN H. TURNER, OF QUINCY, ILLINOIS.

Design No. 3,257, dated November 17, 1868.

DESIGN FOR A TRADE-MARK.

The Schedule referred to in these Letters Patent and making part of the same.

To all whom it may concern:

Be it known that I, EDWIN H. TURNER, of the city of Quincy, county of Adams, and State of Illinois, have originated and designed a new Design for a Trade-Mark, of which the following is a full, clear, and exact description.

Description.

On the ends, two columns wreathed with flowers, and partially draped with fringed curtains.

At top, "Crown Jewels," in scroll.

At bottom, "E. H. Turner, Louisiana, Mo."

In the centre, a crown on a cushion, with a sword and sceptre; and on a scroll partially unrolled, with a pen resting on the same, "E. H. Turner, manufacturer."

Claim.

What I claim as my invention, and desire to secure by Letters Patent, is—

The design for a trade-mark herein set forth.

EDWIN H. TURNER.
